UNITED STATES PATENT OFFICE.

ALEXANDER COLE, OF LYMM, ENGLAND.

FIBER BOARD AND LIKE BOX.

Application filed July 19, 1921. Serial No. 485,944.

(GRANTED UNDER THE PROVISIONS OF THE ACT OF MARCH 3, 1921, 41 STAT. L., 1318.)

To all whom it may concern:

Be it known that I, ALEXANDER COLE, a subject of the King of Great Britain and Ireland, and resident of Lymm, in the county of Chester, England, have invented certain Improvements in Connection with Fiber Board and Like Boxes (for which I have filed application in England, Mar. 5, 1920, Patent No. 165,909), of which the following is a specification.

This invention relates to improvements in or in connection with fiber board or like boxes, the object being to provide means whereby the various parts of the boxes can be readily secured together by the user of the box without the necessity of his employing expensive machinery to do so, a further object being to do away with the necessity of the box manufacturer sending boxes built up which, owing to the space they occupy and their lightness, take up considerable space during transport and are charged by the railway companies at a very high rate. Apart from these high charges the boxes, being empty, are liable to damage during transit.

Prior to the date of my invention the class of trade in these boxes has been carried out mainly in one of the three following ways, firstly the box manufacturer stitched up the boxes rigidly in the factory and sent them by road van or rail to the user. Secondly the box maker bent the boxes diagonally so that they would fold flat after they were stitched together, the user opening them and filling them with goods. The diagonal bends which it was necessary to put in these collapsible boxes left them weak and lacking in the required rigidity. Deep boxes of this class were further reduced in strength by having V-shaped cuts taken out of the sides so as to allow them to collapse or fold flat. Thirdly the box makers cut and prepared the boxes by bending, slotting, cornering and the like, and sent them out unstitched. These are known in the trade as "flats." In this case the user of the boxes has to provide himself with a stitching or riveting machine with which to connect the parts of the box by stitches or rivets before he can use them. These machines are difficult to obtain at the present time and are likewise very expensive.

The object of my invention is to enable boxes sent out in the flat or collapsible state to be readily built up and the parts secured together without the use of expensive machinery and with nothing necessary in the way of tools beyond a hammer and a suitable form of projecting bed or anvil for supporting the box material during the making-up process. The invention is not, however, confined to box material or boxes sent out in the flat state as it likewise applies to boxes which are made up and having lids which require securing after the material has been packed in the boxes.

My invention will be fully described with reference to the accompanying drawing which indicates by way of example how my invention may be carried out and in which,

Fig. 1 is a plan of a developed box blank,

Fig. 2 is a partial sectional elevation of the box blank showing one form of connecting means in the unclinched position.

Fig. 3 is a similar view to Fig. 2 with the connecting means clinched,

Fig. 4 is a plan of the staple device shown in Figs. 2 and 3,

Fig. 5 is a partial sectional elevation of the box blank showing another means of connecting the parts, and

Fig. 6 is a perspective view showing the application of the invention to a collapsible box of the carton or skillet type.

To the aforesaid end my invention consists in providing those parts of the boxes which are normally secured together by stitching or by staples with bifurcated rivets *b* Fig. 5, staples *c*, Figs 2 and 4, or kindred securing means pressed through parts *a* of the boxes which are to be secured to other parts. The bifurcated rivets, or the like are first pressed through the box material and have their inner ends *d* slightly splayed outwardly when being pressed through one or more (usually one) thickness of the box material, though in some cases the ends as in those of staples *c* may be bent inwardly (Fig. 2), the object of the splaying or bending being firstly, to hold the rivets or staples in position during transit and likewise ready to be driven completely through the other parts of the boxes to secure them together and secondly to facilitate the clinching of the bifurcated rivets or staples (Fig. 3) on a

flat anvil or mandril. In securing the parts together it is only necessary to use a projecting anvil secured to a bench and a hammer to drive the bifurcated rivets or staples home.

Fig. 6 shows the application of the invention to a collapsible box of the carton or skillet type, the rivets *b* being attached to the outer one of the folding end flaps *e*.

- 10 Prior to placing the bifurcated rivets, staples or the like in position in the box material the latter is bent, slotted or cornered. In fact everything is done to the material to enable it to be easily folded into position for having the parts secured in the manner described. The bifurcated rivets or staples are pressed into the box material during manufacture by the use of the ordinary box-making machines for the purpose,
- 15 20 such machines being slightly altered in the operative parts to accomplish the splaying

or bending of the rivets or staples with the objects hereinbefore referred to.

What I claim as my invention and desire to secure by Letters Patent is:—

The combination, with a box blank provided with foldable flaps which overlap when the blank is folded to form the box, of bifurcated fastening devices having sharply pointed ends and adapted to secure the overlapping flaps together in pairs, said fastening devices being forced into one flap of each pair and partially expanded while the blank is flat so as to hold them connected to it, said fastening devices being adapted to be forced through the other flap of each pair and fully expanded when the blank is folded to form the box.

In testimony whereof I have hereunto set my hand.

ALEXANDER COLE.
